PROTECTIVE DEVICE IN TELEVISION RECEIVERS

Original Filed Nov. 13, 1933

Inventor:

Manfred von Ardenne

UNITED STATES PATENT OFFICE

2,188,290

PROTECTIVE DEVICE IN TELEVISION RECEIVERS

Manfred von Ardenne, Berlin, Germany

Original application November 13, 1933, Serial No. 697,739, now Patent No. 2,096,987, dated October 26, 1937. Divided and this application October 14, 1936, Serial No. 105,626. In Germany November 15, 1932

1 Claim. (Cl. 250—27)

The invention relates to the particular embodiment of mains apparatus for delaying the initiation of the anode potential in Braun tubes. The use of indirectly heated cathodes in tube apparatus, in Braun tubes, acts detrimentally on the life thereof, owing to the long time required for heating the cathode, if the full anode potential becomes effective before the cathode has attained a sufficiently high temperature. Now when using normal mains apparatus the anode potential acquires its full voltage almost instantaneously, whereas the temperature of the cathode, and together therewith the emission, increases only very slowly, and frequently does not attain a sufficiently high value until after an elapse of several minutes.

This application is a division of application Serial No. 697,739, filed November 13, 1933, Patent No. 2,096,987, dated October 26, 1937.

In the interval before the complete emission takes place there is produced a particularly strong cathode fall, which leads to a vigorous bombardment of ions and to a greatly shortened life and a deformation of the cathode, similar to the manner in which, as well known, under-heated cathodes are subject to premature wear or damage in tube apparatus. If the heating period amounts, for example, to 1 minute for an indirectly heated cathode, the dangerous state with the bombardment of ions commences, as experiments have shown, after approximately 10 seconds.

Said cathode fall is particularly dangerous because of the relatively small surface of the highly emissive material.

According to the invention, these disadvantages are overcome by special measures preventing the anode D. C. potential from becoming its full value before the cathode has reached a sufficiently high temperature and accordingly an adequate emission.

The present invention will be best understood by the accompanying drawing, in which 1 is the mains transformer, 2, 7 and 12 cathode filament, Wehnelt cylinder and anode of a Braun tube, 5 a rectifier tube having a cathode filament 4 and anode 8. The transformer is provided with three secondary windings of which 6 produces the high alternating tension for the rectifier whilst the two other secondary windings are connected to the heater of the Braun tube via an adjustable re-

sistance 3, respectively to the filament 4 of the rectifier tube 5 via a thermionic time lag device 15. The anode tube 5 is connected to the Wehnelt cylinder 7 and via a biasing resistance 9 to the cathode 2. The condensers 10 and 11 serve for 5 smoothing.

The use of such a time switch device is well known for other purposes for example for limiting the anode current as shown by the British patent specification No. 372,799.

The device 15 may consist, in a well known manner, of a thermic relay operated, for example, by the heating current of the cathode of the Braun tube and actuates a switch closing the 15 heating circuit of the cathode 4 after a certain time.

The possible form of embodiment referred to may undergo numerous modifications within the meaning of the invention. It is essential that in each case a thermic time lag device is provided in order to ensure that the anode potential does not reach its full value until after the elapse of a certain time which is necessary to raise the indirectly heated cathode to a sufficiently high temperature.

I claim:

In a television receiver a mains supply and a Braun tube having cathode filament, Wehnelt cylinder and anode, said mains supply comprising a transformer having a primary winding connected to the mains and three secondary windings, a rectifier tube producing the direct current high tension for the anode and the Wehnelt cylinder of said Braun tube, and smoothing means, one of said secondary windings connected on the one side to the cathode of said rectifier and on the other side to the anode of said Braun tube, the second to the filament of said Braun tube, the third to the filament of said rectifier tube, in the last circuit a thermostatic switch closing the 40 circuit after a certain time interval the anode of said rectifier being connected directly to said Wehnelt cylinder and via a resistance to said cathode of the Braun tube, said smoothing means comprising at least condensers connected on the 45 one hand across the Wehnelt cylinder and the anode and on the other hand across the Wehnelt cylinder and the cathode of the Braun tube.

MANFRED VON ARDENNE. 50
